ENCLOSED SWITCH AND CONTACT THEREFOR

Edwin W. Landmeier, Cincinnati, Ohio, assignor
to The Wadsworth Electric Manufacturing
Company, Covington, Ky., a corporation of
Kentucky

Application October 6, 1938, Serial No. 233,615

1 Claim. (Cl. 200—163)

The present invention relates to switches and has for an object the provision of an enclosed type switch wherein the moving contact and its operating mechanism are simplified and rendered less expensive to produce while at the same time the efficiency and durability of the switch is enhanced over previously known devices.

Another object of the invention is to provide a simplified novel form of moving contact wherein a maximum effective conductivity is attained at reduced cost in material and manufacturing operations.

A further object of the invention is to provide a switch wherein the assembly of the moving contact carrier and its operating crank is greatly simplified.

These and other objects are attained by the means described herein and exemplified in the accompanying drawing, in which:

Fig. 1 is a perspective view showing a switch embodying the invention with a fragment of the side wall of the switch box in operative relation thereto.

Fig. 2 is a view taken on line 2—2 of Fig. 1.

Fig. 3 is a view taken on line 3—3 of Fig. 1.

Fig. 4 is a perspective view of the improved moving contact of the invention.

Fig. 5 is an end view of the device shown in Fig. 4.

Fig. 6 is a side elevational view of the switch blade carrier of the device of Fig. 1 removed from the switch, but having the contact blade in position therein.

Fig. 7 is a perspective view showing a modified form of the switch of the invention.

The switch of the present invention may comprise a suitable insulating base 10 having a slot or way 11, the opposed wall faces 12 and 13 thereof being recessed as at 14 and 15 respectively in order to seat a pair of fixed contacts 16 and 17. In the present embodiment the contact 16 has an angularly turned flange 18 secured in place by a screw 19 which passes through a bore 20 and threadedly engages in a threaded perforation in said flange. The free end of fixed contact 16 is depressible into recess 14 when sufficient pressure is exerted thereon against the yielding resistance of the metal of said contact. The contact 17 has an angularly turned flange 21 secured by threaded engagement therewith of screw 23 which is also entered from the bottom of the switch base through a suitable bore 24. The projecting ends of the screws 19 and 23 are each adapted to receive a loop of conducting wire and a binding nut (not shown) in order to connect the switch 55

of the invention in an electrical circuit to be controlled thereby.

A switch blade carrier 25 formed of strong insulating material such as hard fiber is of such thickness as will enable it to be freely and slidably moved between the adjacent faces of contacts 16 and 17.

In the switch illustrated in Figs. 1, 2 and 3, the blade carrier 25 has an elongated slot 26 therethrough which snugly receives a flat operating bar 27. Spaced from slot 26 and adjacent one edge of insulating blade carrier 25 a substantially rectangular aperture 28 is cut through the carrier 25. A moving contact 29 is floatingly seated in the aperture 28 so that when the carrier is moved between the fixed contacts, the opposed faces of parallel major side walls 30 thereof will effect a snug wiping contact with adjacent faces of contacts 16 and 17. The moving contact 29 forms an important feature of the switch and it distinguishes from previously known and used floating contacts in that the weight of metal employed may be reduced to a minimum. The wall structure of contact 29 is continuous, the major side walls 30 being connected together along opposed edges by the integral end walls 31, thus forming two paths for the flow of current when interposed between fixed contacts such as 16 and 17. The temperature of the cooperating contacts is considerably lower in a given installation utilizing the continuous moving wall contact such as 29 as compared with heretofore known contacts. Contact 29 is formed rapidly and inexpensively and the spacing between outer faces of walls 30 is subject to accurate control, thus assuring smooth operation of the switch in which the contact is employed. The compressive strain imposed upon walls 30 as the contact is slidably moved between the relatively fixed contacts 16 and 17 is uniformly distributed upon the pair of connecting end walls 31 so that there is no likelihood of crystallization and cracking due to continued manipulation of the switch.

In assembling the switch just described, contacts 16 and 17 are secured to the base 10 whereupon the hollow continuous walled contact 29 is seated in aperture 28 and the carrier is then slipped into the slot in base 10 whereupon the opposed walls of the slot 11 preclude further displacement of contact 29. The flat rod 27 is then entered into slot 26 in the carrier 25 and into suitable bearings which may be formed in the cabinet wall 32 or any other wall structure associated with the switch. By turning operating bar 27 on its longitudinal axis, carrier 25 is

raised between contacts 16 and 17 until the captive floating contact 29 is positioned between and in contact with said fixed contacts. In opening the switch the movement is reversed and the body of the fiber blade carrier 25 descends between the fixed contacts to suppress arcing at the contacts. As aforesaid, the heating of the contacts as a result of switching operations is considerably lower, and this together with the suppression of the arc is not only minimizes the danger of burning the contacts but the wear due to the friction of wiping contact is likewise reduced to a minimum because of the compensating self-adjustment of the moving contact 29 in the direction of the thickness of switch blade carrier 25.

As illustrated in Fig. 1 the bearing for operating rod 27 may be constituted by the walls of an odd-shaped aperture 33 having arcuate end walls 34 spaced apart at a distance slightly greater than the width of operating bar 27 and connected together by side walls presenting opposed fulcrum points 35 which are spaced apart slightly more than the thickness of operating bar 27. The bar 27 inserted in a pair of apertures such as 33 provides an inexpensive and easily assembled bearing and limit stops controlling the degree of rocking movement of the bar and its associated switch blade carrier 25. A suitable handle crank 36 is formed on one end of bar 27.

It is to be understood that the invention herein is not limited to a structure wherein the insulating switch blade carrier is movable through an arc of a circle. For example, the moving carrier supporting a contact such as 29 may be adapted to rectilinear movement instead of arcuate movement. While the retention of contact 29 is de-

sirable by floating support between the walls of the recess in the carrier and the walls of a slot in which said carrier operates, this floating mounting of either the contact or its carrier, or both may be attained in any other way. For convenience, as shown in the embodiment of Fig. 7, the insulating base 37 may take a form comparable to the base 10 of Fig. 1 and may have the fixed contacts 38 and 39 in the relation described for the corresponding parts in Fig. 1. A strip or carrier of insulating material 40 has an aperture therethrough to receive a moving contact such as 29 adjacent its one end while the remaining end 41 may be of reduced width to enable the passage thereof through a restricted slot in a cabinet wall (not shown) for push and pull operation of the switch from the exterior of such a cabinet. Any suitable handle means such as a bar 42 may be provided on the exteriorly accessible part of the switch blade.

What is claimed is:

An enclosed type switch comprising a slotted base of insulating material, a pair of fixed contacts disposed in the slot adjacent opposite walls thereof, a carrier of insulating material disposed in the slot between said contacts and having an aperture therein adjacent an edge thereof for receiving a moving contact, and further provided with an elongated slot, a flat bar in said slot and a cabinet wall having an aperture therein to receive said bar and presenting opposed fulcrum points on opposite sides of said bar and further presenting arcuate edges restraining edgewise movement of the bar and permitting limited rotational movement thereof.

EDWIN W. LANDMEIER.
